PORTABLE VOLT-AMMETER OR THE LIKE

Takeo Kuramoto, Tokyo, Japan, assignor to Kyoritsu Electrical Instruments Works, Ltd., Tokyo, Japan

Filed Mar. 23, 1970, Ser. No. 22,033

Claims priority, application Japan Sept. 29, 1969

Term of patent 7 years

Int. Cl. D10—10

U.S. Cl. D26—1

FIG. 1 is a front perspective view of a portable volt-ammeter or the like showing my new design;
FIG. 2 is a side view thereof;
FIG. 3 is a front view thereof; and
FIG. 4 is a rear perspective view thereof.

I claim:

The ornamental design for a portable volt-ammeter or the like, as shown.
